CLAIM

The ornamental design for a lotion dispenser, as shown and described.

DESCRIPTION

FIG. 1 is a front top and left perspective view of the lotion dispenser showing our new design;

FIG. 2 is a front view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.

The dashed lines are included for the purpose of illustrating portions of the lotion dispenser that form no part of the claimed design. The dot-dashed broken lines are included for the purpose of illustrating unclaimed borders around portions of the subject matter being claimed.

1 Claim, 4 Drawing Sheets
